CLAIM

The ornamental design for an adjustable target frame, as shown and described.

DESCRIPTION

FIG. 1 is a front perspective view of an adjustable target frame;

FIG. 2 is a right side view thereof in a compacted position, the left side view being a mirror image thereof;

FIG. 3 is a right side view thereof in a raised position, the left side view being a mirror image thereof;

FIG. 4 is a front view thereof;

FIG. 5 is a back view thereof; and,

FIG. 6 is a top view thereof.
